SIGNAL CONTROLLED AMPLIFIER

Le Roy C. Paslay, Chicago, Ill., assignor to National Geophysical Company, a corporation of Delaware

Application August 19, 1937, Serial No. 159,994

12 Claims. (Cl. 177—352)

This invention relates to a signal controlled amplifier, and more particularly to an electronic amplifier adapted to maintain a substantially constant output despite wide variations in the signal input thereto.

One feature of this invention is that it is adapted to maintain a substantially constant average output and yet reproduce individual input oscillations in proportion to those adjacent thereto; another feature of this invention is that it will maintain the average value of an oscillatory output substantially constant when the mean oscillatory input or signal varies uni-directionally through a wide range during a short interval of time; yet another feature is that improved means is provided for automatically varying the gain of the amplifier with respect to time during a pre-determined interval, independently of input variations but inversely thereto; yet another feature of this invention is that it is adapted to regulate the gain of an amplifier by, but inversely to the signals being handled by such amplifier; other features and advantages of this invention will be apparent from the following specification and the drawings, in which:

Fig. 1, comprising the two parts, Figs. 1^a and 1^b, is a circuit diagram of an electronic amplifier embodying the inventions hereinafter described.

While circuits for automatically controlling the output of an amplifier to maintain it substantially constant despite variations in the input are known and in common usage, these are found almost entirely in the radio field where the signal is superimposed upon a carrier. The carrier, as distinguished from the signal envelope, provides a plurality of rapid oscillations which can be rectified to provide a control voltage for one of the elements of a tube having a variable amplification factor, or a plurality of such tubes, and thus control of the output is readily and simply achieved. Where such a carrier is not present, however, and an attempt is made to control the output directly from the signal, various difficulties are encountered with conventional automatic volume control circuits. This is particularly true where the signal frequency is rather low and where the variations in the input cover an exceedingly wide range in a short interval of time. In such a case conventional methods of automatic volume control will, if arranged with a short enough time constant and a wide enough range to be of much value, distort both the wave forms of individual waves and the amplitude relation between succeeding waves.

The present inventions are disclosed in connection with an electronic amplifier particularly designed for use in geophysical exploration work. In such exploration an explosive charge is detonated at a particular point and the vibrations resulting therefrom and transmitted through the adjacent terrain are picked up at various points by seismometers and, after being amplified, recorded in some convenient way, as by a galvanometer on a photographic strip. The resulting record comprises oscillations of low frequency, and from the wave form, time intervals and other data reproduced on the record by the reflections of the same detonation from various strata the geology of the terrain can be deduced.

The physical waves resulting from the detonation and subsequently transformed into electrical energy by the seismometers are of low frequency, generally less than 100 cycles per second; and in an interval of five seconds or less the average or mean amplitude of the input to the amplifier decreases to one ten-thousandth or less of the initial input. This variation in mean signal strength may be described generally as unidirectional, in that it decreases fairly consistently from a strong signal to a very weak one, although it will be understood that the mean signal strength fluctuates somewhat and does not follow a smooth curve, sometimes even increasing slightly for a very short period. In order to make a readable strip record it is readily apparent that some sort of gain control in the amplifier is necessary, yet that conventional automatic volume control circuits will fail to achieve the desired results. Gain control which covers this range without distorting wave form or amplitude relation of adjacent oscillations has been accomplished in the amplifier illustrated herewith by combining an automatic expander, which changes a portion of the gain of the amplifier with respect to time independently of the signal, with a portion of the amplifier wherein automatic volume control means changes the gain by, but inversely to, the signal, in accordance with the average value thereof. This automatic volume control portion comprises two parts, one of which follows the signal envelope rather closely to generate the rectified control voltage, the other serving as the main amplifying channel developing the output of the unit and being controlled substantially in accordance with the average amplitude of the oscillations by the voltage generated in the other portion.

In the particular embodiment of the invention illustrated herewith the input portion of the

amplifier, prior to the first tube, is shown in Fig. 1^a. This comprises various relays, resistors, transformers, and the like, making an operative input system capable of adjustment with respect to the proportion of the input signal fed to the first tube, and an expander circuit adapted to vary a portion of the gain of the amplifier inversely to the signal variation during the same time interval, the operation of the expander being initiated by the "first break" or initial input, but thereafter being independent of the signal. The portion illustrated in Fig. 1^b comprises tubes arranged in cascade to provide a main signal amplifying channel and other tubes arranged in a circuit operatively coupled to the main channel for achieving, from the voltages of the signal envelope, a volume control which varies the main channel gain in accordance with but inversely to the mean or average signal amplitude.

Referring more particularly to Fig. 1^a, an input plug 10 is shown having terminals 12, 13, 14, 16 and 17, which terminals are adapted to have leads from three different seismometers attached to 12, 13 and 14, the returns being all through a common ground connection to the terminal 17. The terminal 16 is supplied with a potential which, in this particular case, is six volts negative with respect to chassis ground. This voltage serves to render an expander, hereinafter to be described, operative.

The group of switches indicated in general as 18 are adapted to be manually operated for test purposes, and will not be further described. The switches in the group indicated in general as 19 are for the purpose of achieving the necessary switching to, in connection with the three transformers 20, 21 and 22, place the input circuit in condition to enable three seismometer circuits to be connected together to form one trace, to have only one seismometer circuit providing input energy to the amplifier, or in combination with the relay 23, to provide energy for a period from one seismometer circuit, and then for the remainder of the period from three. When the relays 19 are in the position illustrated in the diagram, input from only one seismometer circuit is supplied to the amplifier until the group of relays 23 has shifted, which occurs a predetermined time interval after the first break, and the input energy is then taken from three such circuits.

All of the movable armatures of the relay group 23 are actuated by the one relay coil 24 so that they all swing at once in response to energization thereof. Means for energizing this actuating coil upon the initial input signal or first break when a charge is fired may be accomplished by any desired means, not here shown. Such means should, however, be unresponsive to transient voltage variations prior to the detonation, and is preferably arranged so that there is some slight time interval after the detonation before the operation of the relay. The group of switches 23 forming the relay is here shown in the position in which they would be before detonation of the charge; after the initial input energizes the relay all of the movable armature members thereof would swing to the left, speaking with respect to their positions as illustrated, and held there for the duration of the signal.

In order to reduce the first break input voltage to the tubes prior to operation of the relay, a resistor assembly 25 is employed. In the particular arrangement illustrated here any one of

the resistors, which vary in value from about 5 megohms down to about 150 ohms, may be placed in series with the seismometer input circuit, but they are adapted to be shorted out upon operation of the relay 23 by closing of the contacts of the switch 23^b. It will be understood that the resistor assembly should be arranged either in series or parallel with the seismometer cables in accordance with whether the impedance characteristics are inductive or capacitative, in order to keep cross feed or coupling between the cables as low as possible.

The use of three transformers 29, 21 and 22 for the input with separate load resistors 26, 27 and 28 connected across the secondaries thereof permits the addition of voltages across these resistor loads without undesired coupling between the seismometer circuits. These load resistors, moreover, are of a variable type as shown adapted to permit manual attenuation of the input signal to insure the desired output from the amplifier. The fact that this main attenuator is located ahead of the first tube of the main amplifier channel enables overloading of this first stage to be prevented. Any desired portion of the alternating voltage developed across the load resistors is taken through the wire or lead 29 to the grid element of the first amplifier tube.

One of the novel and particularly important portions of the amplifier disclosed herewith is the expander circuit comprising the condenser 30, resistors 31, 32 and 33, and the switch elements 23^a. Resistors 32 and 33 are so chosen that their ratio is as the ratio of the desired residual or terminal grid voltage to the voltage applied through the terminal 16. In the present case the desired terminal voltage is one volt negative, a 6-volt negative potential is applied to the terminal 16, and the resistors have a one to five ratio, the resistor 32 being 40,000 ohms and the resistor 33 having a value of .2 megohm, for example. It will be noted that the resistor 33 is a potentiometer, the potential at any point thereof being applied through the wire 34, the switch elements 23^a, and the wires 35 and 36 to the upper side of the condenser 30 and to the secondary of one of the transformers, at 21. Inasmuch as the other side of the condenser 30 is connected to the wire 37, which wire forms the chassis ground, the potential existing across the condenser, depending upon the setting of the variable resistor 33, is applied between the cathode and grid of the first amplifier tube to determine its initial sensitivity. As long as the circuit is complete through the switch points 23^a the condenser 30 remains at the chosen potential. As soon as this circuit is broken upon operation of the relay 23, however, the condenser starts to discharge through the resistors 31 and 32, and thus the bias voltage applied by it to the grid decreases toward chassis ground potential. The time interval taken for the drop in voltage from the initial bias voltage to essentially the terminal bias voltage determined by the resistor 32, with any given initial voltage, is a function of the size of the condenser 30 and the value of the resistors 31 and 32 through which it must discharge. The condenser 30 may, for example, be .25 micro-farads and the resistor 31 one megohm. The value of the resistor 32 is substantially negligible in such a case, and the discharge time effective to vary the gain of the tube 38 may be considered as a function of the resistor 31. In the case shown the expansion

time in seconds is approximately twice the value of the resistor 31 in megohms. With the resistor shown, the voltage across the condenser 30, applied to the grid of the first tube as a bias, would vary from its initial to essentially its terminal value in about two seconds.

Referring more particularly to Fig. 1^b, it will be seen that the first or initial tube 38 is a high gain pentode tube of the variable mu type. Where the amplifier is designed for use as a battery operated unit this tube may, for example, be of the 6K7 type. The characteristics of this tube are such that a 5-volt change in grid bias is sufficient to vary the amplification factor of the tube considerably. In the particular circuit illustrated the expander will, if the initial sensitivity control 33 is set to apply all of the available negative bias to the grid at the beginning of the expansion period, vary the amplification factor of the tube 38 about thirty-four to one in the 2-second interval.

It will be seen that once action of the expander, varying the amplification factor with respect to time, is initiated the amplification factor of the tube will rise from its initial value to one about 34 times that during the interval. Once this change has been started by operation of the relay 23 it is independent of the signal. That is, the rate of change is determined by the discharge of the condenser through the resistor 31, which is a function of time, and is not dependent in any way upon the rate of change of the average signal or any individual oscillation thereof during the time interval. It will be understood, however, that when the expander action is spoken of as being independent of the signal it is merely meant that the rate of change is a fixed function of the condenser and resistor, since initiation of the expander action is dependent upon the first break or initial signal, and the terminal voltage may, if desired, also be made a function of the signal. The time interval through which it is desired to have the amplifier operate to produce a record, in conjunction with a camera oscillosograph, depends upon the terrain in which the charge is detonated. The time interval from first break to the final reflection which is of any value may run from one second up to about four seconds, but is generally between two to three seconds. The rate of change of the expander voltage with respect to time should be set for approximately the same interval by changing the value of the resistor 31.

The use of such an expander, changing the amplification of at least one tube with respect to time, is of considerable advantage, particularly where it is coupled with automatic volume control in later portions of the amplifier. It has been found that too great automatic volume control results in many difficulties, both from the standpoint of poor records and of circuit instability. The use of an expander of this type ahead of the automatic volume control portion of the circuit, however, enables the automatic volume control system to carry a much smaller portion of the burden. In the present case, for example, the automatic volume control need only have a maximum change in gain of one-thousand to one to give the amplifier an over-all variable gain more than sufficient to handle any variation in signal input which will be likely to be encountered in the field. The initial sensitivity adjustment enables the sensitivity to be so adjusted as to eliminate wind and other transient sounds prior to the first break at the detonation.

Referring more particularly to the portion of the device comprising the electronic amplifying tubes, it will be seen that there is a main amplifier channel comprising the tube 38, the two tubes 39 and 40 arranged in push-pull relation, and the output tube 41 feeding into the output coupling transformer 42 leading to the camera oscillosograph. The transformer 43 handling the output of the driver tube 38 has two secondaries, one being connected to the tubes 39 and 40 and the other supplying energy to the grid elements of another pair of tubes 44 and 45 arranged for push-pull operation. The output of these latter tubes is fed to the tube 46, and these three last mentioned tubes serve as an auxiliary system providing automatic volume control bias to achieve the desired control of the over-all gain of the push-pull stage in the main channel of the amplifier. The tubes 39, 40, 44 and 45 are also here shown as of the 6K7 type, while the tube 46 is a duo-diode-triode tube of the 6Q7 type. The tubes in each of these push-pull stages must be of similar characteristics and each pair must be carefully balanced, so that changes in grid or control bias will be neutralized and will not cause such unbalancing of plate current as to be reflected in the record as a signal. The transformers and other circuit elements should be so selected that the frequency response in the auxiliary or AVC portion of the amplifier is nearly the same as that in the main amplifying channel, having preferably a slightly higher cut-off.

The various tubes and associated portions of the circuit are supplied in conventional manner with the necessary voltages to render the device operative, usually by batteries when the device is being used in the field for geophysical work.

The screen grids are preferably supplied with voltage through a separate battery connected to the lead wire 47, rather than by a portion of the plate voltage supply, since small changes in screen grid voltage in tubes of this type will cause a change in the amplification factor.

The impedance of the grid circuits of the push-pull stages is made high by the use of resistors 48, 49, 50 and 51, to prevent the surge at the first break, when the sensitivity and gain of the main portion of the amplifier is high and the grids of the push-pull stages are swung positive, from permitting enough current to flow into the condensers 52 and 53 to cause them to block the tubes for an undesired interval thereafter. These resistors may all, for example, have a value of one megohm.

If too large an amount of energy is fed in to the push-pull stages for a few tenths of a second by the early signal the AVC section of the amplifier will build up so much control voltage that it reduces the gain of the amplifier to such a point that weak signals following the series of first strong impulses will be of too small magnitude. This condition is a result of the accommodation or over-all change of gain ratio of the amplifier being too great, so that the control voltage becomes disproportionately large with respect to the signal input. This is undesirable, and the initial sensitivity setting should be changed so that more accommodation will be taken care of by the expander, or the series resistor increased to cut down the input to the first tube.

Referring more particularly to the auxiliary amplifier for the automatic volume control voltage, it will be seen that the tubes 44 and 45

feed into the transformer 54 having the load resistor 55 across the secondary thereof, the voltage developed across this resistor being applied between the cathode and grid of the triode portion of the tube 46. The output of the triode portion is developed across the transformer 70 which has its secondary connected to the diode elements of the tube to achieve full wave rectification. Since the cathode for the diodes is not directly connected to chassis ground, but rather through the resistors 56 and 57, a delay action is achieved. These resistors should be so chosen as to make the cathode about three volts positive with respect to ground, so that there is no rectification until the voltage across the secondary of the transformer 70 exceeds six volts. The rectified control voltage, developed across the resistor 58, is applied through a small battery (to insure the desired initial bias on the tubes) and the filter resistor 60 through the resistors 60 and 51 to the control grids of the tubes 44 and 45 respectively, in the auxiliary portion of the amplifier. It will be noted that the lead 61 which connects the filter resistor 60 to the resistors 50 and 51 is connected to chassis ground 37 through the condenser 53. Before any appreciable voltage is applied to the grids of the tubes 44 and 45, therefore, the condenser 53 must be charged to that voltage. The time constant of the auxiliary portion of the circuit is thus a function of the filter resistor 60 and of the condenser 53.

The total available grid bias voltage, developed across both the resistors 58 and 59, is transmitted through the filter resistor 62 and the lead 63 to the resistors 48 and 49, through which it is applied to the grids of the tubes 39 and 40 in the main amplifier channel. The lead 63 is by-passed to chassis ground by the condenser 52, and the time constant of the AVC action in the main channel of the amplifier is thus a function of the resistor 62 and the condenser 52.

In the particular embodiment here shown the resistor 62 is chosen with the value of one megohm and the resistor 60 with the value of one-half a megohm; while the condenser 52 has a value of .1 micro-farad and the condenser 53 of .05 micro-farad. The time constant of the control action in the main channel of the amplifier is about one-tenth of a second, or slightly higher, and the time constant of the automatic volume control or auxiliary portion of the amplifier is about one-fourth of that. The shorter time constant in the auxiliary section of the amplifier enables it to rapidly follow the envelope of the reflection waves in the input, so that the diode voltage truly represents an average value of the proper voltage for a constant average output, dependent upon the mean signal input existing at the secondary of the transformer 43. The time constant in the main channel of the amplifier is sufficiently long enough, however, that individual fluctuations are not followed, but instead there is a relatively slow change in bias approximating the average change of the input to the push-pull stages, so that the decrease in average signal strength during the interval of the reflections is compensated for, yet outstanding single oscillations, whether they be strong or weak, are handled by the main amplifier without distorting their magnitude with respect to other closely adjacent reflections, or other portions of the same reflection. That is, a strong initial alternation at the beginning of a reflection, fol-

lowed by a much weaker alternation, is faithfully reproduced on the record, while at the same time there is a slow change of amplification factor or gain of the push-pull stage of the main channel so that reflections near the end of the interval are amplified sufficiently to be comparable with those first appearing on the record, and easily read. The time constant of the circuit supplying bias voltage to the auxiliary amplifier, to achieve the desired results, should be from $\frac{1}{3}$ to $\frac{1}{5}$ that of the circuit supplying the bias voltage to the main amplifier, and preferably about $\frac{1}{5}$.

The main channel, since it gets more control voltage than the auxiliary channel, can be held to a very nearly constant output; at the same time, the fact that the auxiliary or automatic volume control channel receives the energy from the input to the push-pull stage in the main channel, and is capable of some swing in amplification factor, enables a very true straight line output to be achieved in the main channel by closely following the signal envelope. In fact, the value of the resistor 59 can be increased to the point where a rise in input to the amplifier will actually result in a decrease in output, so that it will be seen that the output may be controlled in any desired manner. Increasing the time constant or time lag too much in the application of the automatic volume control bias to the main channel gives poor amplitude control, in that the change in amplification factor may lag too far behind changes in input. If the time constant is too short, on the other hand, the later legs or alternations of one reflection may be reduced as compared to the first strong legs, so that a record will be had which does not reproduce true conditions.

When it is desired to take a record of a particular detonation the amplifier is first tested to make sure that all of its parts are in proper working order, and to adjust the main attenuator and other circuit variables so that the expected signal input and time interval will be compensated for. This includes adjustment of the resistor 25 in accordance with the expected power of the first impulses; of the main attenuator comprising the portions 26, 27 and 28 in accordance with the expected power of the final impulses; of the variable resistor 33 for the initial sensitivity desired; the choice of the resistor 31 for the time interval expected or found by previous experiments to exist in that locality; and sometimes adjustment of the resistor 64. Proper choice of the resistor 31 enables the expander action to cover substantially the same time interval as the expected variations in input.

When the first impulse reaches the amplifier the tube 38 has a rather low amplification factor, determined by the position of the initial sensitivity setting, and a load resistor of the group 25 is in the circuit. Since there is no signal passing through the amplifier, however, the automatic volume control is inactive and the gain of the push-pull stage in the main channel is rather high, so that a considerable amount of energy is capable of being developed in the output. In order to prevent this from damaging the galvanometer employed to make the record, generally of the string type, a deflection limiter is included in the circuit. This deflection limiter is shown as comprising a pair of rectifiers 65 and 66 connected back to back in conjunction with a resistor 67. These rectifiers are biased by the

voltage developed in resistor 67 so that the input must exceed the bias voltage, below that which would damage the galvanometer, before rectification occurs, but when the peaks of the first few alternations pass this break down voltage which is substantially a short circuit is placed on the output. The deflection limiter is in series with the switch elements 23^c of the relay 23, however, and as soon as the relay operates the deflection limiter is cut out of circuit. This is generally about one-tenth of a second, and in this time or less the automatic volume control has reached equilibrium and is capable of controlling this input intensity. Upon operation of the relay other events take place, including cutting out the particular resistor in the assembly 25 in series with the input by the switch elements 23^b, and initiation of expander action by the switch elements 23^a. That is, when these latter elements break, the condenser starts to discharge to increase the amplification factor of the tube 38.

An amplifier is thus provided particularly adapted for work of the type where there is no carrier, and control of a wide variation in gain of the amplifier must be achieved by the signal. At the same time, the system is so arranged that good quality is retained, the wave form is not distorted, and the relative magnitudes of adjacent alternations or legs of a reflection are reproduced in comparable magnitude upon the record.

While I have described and claimed certain embodiments of my invention it is to be understood that it is capable of many modifications, changes, therefore, in the construction and arrangement may be made without departing from the spirit and scope of the invention as disclosed in the appended claims in which it is my intention to claim all novelty inherent in my invention as broadly as permissible in view of the prior art.

I claim:

1. An electronic amplifier of the character described adapted to maintain a substantially constant output when the mean signal input thereto varies substantially uni-directionally through a wide range during an interval of time, including: an amplifier having at least two tubes in cascade; means independent of said signal for automatically varying the gain of at least one tube inversely to said input during said interval; and means for varying the gain of at least one succeeding tube by but inversely to said signal variation.

2. An electronic amplifier of the character described adapted to maintain a substantially constant output when the mean signal input thereto varies substantially uni-directionally through a wide range during an interval of time, including: an amplifier having at least two tubes in cascade; means independent of said signal for automatically varying the gain of at least one tube inversely to said input during said interval; means for rendering said automatically varying means operable substantially simultaneously with initiation of said input variation; and means for varying the gain of at least one succeeding tube by said mean signal variation but inversely thereto.

3. An electronic amplifier of the character described adapted to maintain a substantially constant output when the mean signal input thereto varies substantially uni-directionally through a wide range during a short interval of time, including: a plurality of amplifying tubes in cascade, at least two of said tubes having variable amplification factors; means for impressing a

voltage on an element of one of said tubes having a variable amplification factor to control the amplification factor thereof; means for varying said voltage said variation being a function of time only, said last mentioned means being arranged to effect a variation in said amplification factor inverse to said variation of the input and coincident therewith; means for impressing a voltage on an element of the other of said tubes having a variable amplification factor to control the amplification factor thereof, this tube succeeding the first mentioned tube with a variable amplification factor; and means for varying said last-mentioned voltage by said signal variation but inversely thereto.

4. Apparatus of the character described for amplifying an oscillating signal and maintaining a substantially constant mean output when the mean signal input thereto varies widely, including: a main amplifier adapted to furnish said output, said amplifier having a variable gain; an auxiliary amplifier having a variable gain; means for rectifying the output of said auxiliary amplifier to provide a control voltage; and a circuit applying said control voltage to said amplifiers to vary the gain thereof, the time constant of the application to said main amplifier being several times that to said auxiliary amplifier.

5. Apparatus of the character described for amplifying an oscillating signal and maintaining a substantially constant mean output when the mean signal input thereto varies widely, including: a main amplifier adapted to furnish said output, said amplifier having a variable gain adapted to be controlled by a bias voltage; an auxiliary amplifier having a variable gain adapted to be controlled by a bias voltage; means for rectifying the output of said auxiliary amplifier to provide a bias voltage; a circuit applying said bias voltage to said main amplifier, said circuit including a resistance element and a condenser element; and a second circuit applying at least a portion of said bias voltage to said auxiliary amplifier, said circuit also including a resistance element and a condenser element, at least one of said elements having a lesser value than the corresponding element in said first circuit.

6. Apparatus of the character described for amplifying an oscillating signal and maintaining a substantially constant mean output when the mean signal input thereto varies widely, including: a main amplifying channel adapted to furnish said output, said channel comprising a plurality of tubes arranged in cascade, each of said tubes having a cathode, grid, and plate element and at least one of said tubes having an amplification factor variable in accordance with a bias voltage applied between the cathode and the grid thereof; an auxiliary amplifying channel, said channel comprising at least one tube having a cathode, grid, and plate element and having an amplification factor variable in accordance with a bias voltage applied between the cathode and grid thereof; means for diverting a portion of said signal to said auxiliary amplifier from said main channel prior to at least one of the tubes therein having a variable amplification factor; means for rectifying the output of said auxiliary amplifier to provide a bias voltage; a circuit applying said bias voltage to at least one of the tubes in said main channel subsequent to said diversion, said circuit including a condenser in shunt between the cathode and grid of said tube and a resistance in series with one of said tube elements; and a second circuit applying the bias voltage to the

tube elements of said auxiliary amplifying channel, said second circuit including a condenser and resistance similarly arranged but having values such that the time constant of said second circuit is about one-fifth that of said first circuit.

7. Apparatus of the character claimed in claim 6, wherein the oscillating signal has a frequency of less than 100 cycles per second and the first circuit has a time constant of about one-tenth of a second.

8. Apparatus of the character described for amplifying an oscillating signal of a low frequency and for maintaining a substantially constant mean output when the mean signal input thereto varies widely, including: a plurality of electronic tubes arranged in cascade for amplifying said signal to furnish said output, at least two of said tubes having a variable amplification factor; auxiliary amplifying means; means for diverting a portion of said signal to said second amplifier; means for rectifying the output of said auxiliary amplifier to furnish a signal controlled voltage for varying the amplification factor of a tube in said cascade of tubes; a second source of bias voltage adapted to control the amplification factor of a tube in said cascade earlier than that to which said signal controlled voltage is applied; and means for automatically varying said bias voltage with respect to time and independently of said signal.

9. Apparatus of the character claimed in claim 8, wherein said signal is diverted between said time controlled and said signal controlled tubes and the variation in gain of the time controlled portion of said amplifier is less than that of the signal controlled portion.

10. Apparatus for controlling the amplification of signals varying in average amplitude in accordance with time, which comprises an amplifier for said signals, gain control means for varying 40 the amplification of said signals as a function of

time, and monitoring means operating upon the amplified signals which have been subjected to said gain control means for further controlling the amplification as a function of the strength 5 of said last mentioned signals, whereby output signals of substantially constant average amplitude are obtained.

11. Apparatus for controlling the amplification of signals of gradually decreasing amplitude, 10 which comprises an amplifier for said signals, gain control means for increasing the amplitude of the amplified signals in rough accordance with the gradually decreasing amplitude of the original signals, whereby signals having decreased 15 variation of average amplitude are obtained, and monitoring means operating upon the amplified signals which have been subjected to said gain control means for further controlling the amplification as a function of the strength of said last 20 mentioned signals, whereby output signals of substantially constant average amplitude are obtained.

12. An amplifier system for use in seismic surveying which comprises an amplifier operating 25 upon signals varying in average amplitude in accordance with the average amplitude of seismic waves of gradually decreasing average amplitude, gain control means for increasing the amplification of the signals in rough accordance 30 with the gradually decreasing amplitude of the original signals, whereby signals having decreased variation of average amplitude are obtained, and monitoring means operating upon the amplified signals which have been subjected to 35 said gain control means for further controlling the amplification as a function of the strength of said last mentioned signals, whereby output signals of substantially constant average amplitude are obtained.

LE ROY C. PASLAY.
